84 Patented Sept. 12, 1933

1,926,407

placed asbestos and glassine rolls or metal strips
against the glassy or shiny side of the insulating coating
and the glassy or shiny side of the filament.

for the silicon dioxide to combine chemically with the tantalum pentoxide so that the silicon dioxide coating not only becomes firmly attached to the filament by reason of the fact that it 5 hardens against the roughened oxide surface but the tendency to combine chemically makes an integral connection between the two which cannot be impaired, due to differences of the coefficients of expansion of the metal and coatings. 10 Another result produced by this temperature is that the particles of silicon dioxide at the outer surface thereof sinter or fuse together to form an extremely hard surface of silica which increases the dielectric strength of the coating and 15 also provides a better radiating surface for the heat, which is desirable, as no matter how close the cathode is placed with respect to the filament, there will always be some places which do not touch and which will then depend on radiated heat for energization.

The coating on the filament has an extremely high dielectric strength and is also exceptionally thin, the thickness thereof not necessarily exceeding .05 millimeters. The filament so coated 20 may be placed inside of a cathode tube which is just sufficient in diameter to permit the filament to be slipped thereinto and which will closely engage the sides of the filament with no danger at 25 all of the insulating coating breaking down with 30 differences of potentials commonly used between the filament and cathode.

While I have described the use of silicon dioxide in a solution of sodium silicate, other substances may be used with good results, if desired. For instance, aluminum, magnesium or 35 boric oxides may be used, but silicon, having a very high dielectric strength, is preferable. Also, the binder of sodium silicate is preferred because it requires a very small concentration to bind 40 the particles of silicon dioxide together and it releases a minimum of gas vapors during the life of the tube. Other binders, however, could be used, such as resinous or organic types, the necessary feature being merely that the binder hold 45 the particles of silicon dioxide to the oxide coating of the filament until the filament is ready to be used.

The surface of the metal filament is best prepared to receive the silicon dioxide by forming 50 an oxide upon it, as indicated above. It is possible, however, to place the silicon dioxide directly upon the metallic filament without forming the oxide, but I have found that in so coating the 55 filament the silicon dioxide cannot be as uniformly distributed, nor will it adhere to the surface as well, due to surface tension and other effects, and the resulting coating is liable to chip and peel when the filament expands and contracts under temperature changes. It is within 60 the spirit of the invention, however, to include the use of the dielectric applied directly to the filament.

It is evident from the above description that 65 I have provided an insulated coating for a filament wire which may be easily applied to the wire and which produces an insulation having a very high dielectric strength which will not break down under differences in potential of the 70 cathode and filament which are ordinarily used in vacuum tubes, and which coating is so thin that the cathode may be positioned in close proximity to the filament, thus reducing the heat losses to a minimum. 75 The coating has in effect a homogeneous structure ranging from the metal core at the center to

pure silica at the surface, the particles being either chemically combined or physically closely adherent.

While I have described the invention in connection with certain specific substances, it is evident that many changes may be made in the materials and combinations of materials used, so that I do not desire to limit myself to the specific substances described but to interpret the invention broadly within the scope of the appended claims.

Having thus described my invention, what I desire to claim is:

1. The method of insulating a heater element for an indirectly heated cathode in an electron discharge tube which comprises forming an oxide on the surface of said element, immersing said element, in finely divided silicon dioxide suspended in a liquid binder, the silicon dioxide being greatly in excess of the amount of solid material in said binder, and heating said element to harden said silicon dioxide and effect the combination of said oxides. 90

2. The method of insulating a metal filament which comprises heating said filament in an oxidizing atmosphere to form an oxide thereon, coating said oxide with finely divided silicon dioxide suspended in a very weak solution of sodium silicate and heating said filament to harden said silicon dioxide. 100

3. The method of insulating a filament which comprises heating said filament in an oxidizing atmosphere, coating said filament with finely divided silicon dioxide suspended in a very weak solution of sodium silicate and heating said filament, whereby the surface of said silicon dioxide is fused. 105

4. A heater element for an indirectly heated cathode in an electron discharge tube, a coating of oxide on said element and a second coating on said oxide of an electrical insulating substance having a greater dielectric strength than said oxide, said second coating having a tendency to combine chemically with said oxide and thereby obtain integral connection of said coating with the heater element through the agency of said oxide coating. 115

5. A heater element for an indirectly heated cathode in an electron discharge tube, an oxide forming a coating on said element and a second coating on said oxide comprising an electrical insulating substance having a higher dielectric strength than said oxide and combined therewith. 120

6. A heater element for an indirectly heated cathode in an electron discharge tube, an oxide coating on the surface of said element and a second coating of finely divided silicon dioxide closely associated with said first coating. 130

7. A metallic heater element for an indirectly heated cathode in an electron discharge tube, an oxide formed on the surface of said element and a coating of silicon dioxide physically and chemically associated with said oxide. 135

8. A metal heater element for an indirectly heated cathode in an electron discharge tube, an oxide formed on the surface of said element and a coating on the surface of said oxide comprising finely divided silicon dioxide with a binder of a relatively much smaller amount of sodium silicate. 145

9. A tantalum heater element for an indirectly heated cathode in an electron discharge tube adapted to be used in a vacuum tube, a coating 150

84

1,926,407

3

- of tantalum pentoxide on said element, a coating of silicon dioxide physically and chemically combined with said oxide coating and a hard, fused surface on said silicon dioxide.
- 5 10. The method of insulating a heater element for an indirectly heated cathode in an electron discharge tube which comprises forming an oxide coating on the surface of a filament of metal having a melting point above 1600° C., coating 10 such oxidized surface with material consisting very largely of an oxide having a melting point above 1600° C. and high dielectric strength and a relatively much smaller amount of a binder and heating sufficiently to bring about partial 15 chemical reaction between the materials of said coatings and adhesion between such materials and the metal of the filament.
11. The method as in claim 10 in which the metal of the filament consists chiefly of tantalum 20 and the first oxide coating is formed by oxidizing the metal of the filament.

12. The method as in claim 10 in which the second oxide coating consists very largely of free silica.

13. The method as in claim 10 in which the binder consists chiefly of a relatively readily fusible silicate. 80

14. The method as in claim 10 in which the metal of the filament consists chiefly of tantalum.

15. The method of insulating a heater element for an indirectly heated cathode in an electron discharge tube, which comprises heating a filament consisting chiefly of tantalum in an oxidizing atmosphere to produce a layer of tantalum pentoxide, coating the oxidized surface with silicon dioxide mixed with a relatively much smaller amount of alkali silicate and heating sufficiently to bring about partial chemical reaction between the materials of said coatings and adhesion between such materials and the metal of the filament. 85 90 95
